(57) **CLAIM**

The ornamental design for a wrist watch case, as shown and described.

DESCRIPTION

FIG. 1 is a perspective view of a wrist watch case showing my new design;

FIG. 2 is a front elevation thereof;

FIG. 3 is a rear elevation thereof, certain working parts inside of the watch which are not being claimed, including everything inside of the two circular windows on the back of the watch and everything inside the non-circular window located above the two circular windows, is intended to be in broken lines and therefore everything inside these three windows are not part of the claimed invention;

FIG. 4 is a right side view thereof;

FIG. 5 is a left side view thereof;

FIG. 6 is a bottom view thereof; and,

FIG. 7 is a top view thereof.
